(57) **CLAIM**

The ornamental design for a tilt bin cover, as shown and described.

DESCRIPTION

FIG. 1 is a perspective view of a tilt bin cover showing our design;

FIG. 2 is a front elevation view;

FIG. 3 is a rear elevation view;

FIG. 4 is a right side elevation view; the left side elevation view being a mirror image; and,

FIG. 5 is a top plan view.

The broken-line disclosure in the views represents portions of the tilt bin cover in which the claimed design is embodied, but which form no part of the claimed design.
